UNITED STATES PATENT OFFICE.

FREDERICK O. PEASE, OF CHICAGO, ILLINOIS.

STRINGED MUSICAL INSTRUMENT.

Application filed April 25, 1923. Serial No. 634,459.

To all whom it may concern:

Be it known that I, FREDERICK O. PEASE, a citizen of the United States, residing at Chicago, in the county of Cook and State of Illinois, have invented certain new and useful Improvements in Stringed Musical Instruments, of which the following is a specification.

This invention relates, generally, to 10 stringed musical instruments, but while it has particularly relation to pianos of various types, such as grand, upright, and player piano types, and is shown in the accompanying drawing in connection with an upright 15 piano, and will hereinafter be so described and explained, yet I desire it to be understood that certain features of the invention are applicable for use in connection with other instruments having fixed strings tuned 20 in scales, chromatics, chords, or tunes, such as zithers, dulcimers, auto harps and analogous instruments, without a departure from the spirit of the invention.

One of the objects of the invention is to 25 furnish a musical instrument which by reason of the utilization of my improvements, shall possess high tonal qualities and shall be simple, durable, and inexpensive in construction, with its parts so made, arranged 30 and operable with respect to one another as to be positive and dependable in action.

Another object of the invention is to provide means in a musical instrument whereby 35 certain musical effects, such as exceptional tonal values, sweetness and flexibility of expression, and ease of execution can be produced, without requiring any change in technique, but by simply employing the 40 pedals of the instrument to control or operate certain elements of the invention, or as predetermined by the perforated record in player pianos.

Another and important object of the invention is to provide means for greatly improving the tonal quality of the higher or 45 last two octaves over that of instruments heretofore and at present in general use.

Other objects and advantages of the invention will be disclosed in the following 50 description and explanation, which will be more readily understood when read in conjunction with the accompanying drawings, in which is illustrated an embodiment of the invention, it being understood that 55 modifications and changes may be resorted to without a departure from the invention,

so long as they fall within the scope of the appended claims forming a part hereof.

In the accompanying drawings,—

Fig. 1 is a face view of the metallic frame 60 or plate and the sounding board of an upright piano of about the ordinary construction showing enough of the strings of the instrument mounted thereon for illustration and showing my improvements arranged in 65 substantially the positions they will occupy when in practical use on a piano.

Fig. 2 is an enlarged view of a modified fragment of like parts shown in Fig. 1, with 70 the higher or last two octaves of the treble strings omitted.

Fig. 3 is a sectional view taken on line 3—3 of Fig. 2 looking in the direction indicated by the arrows.

Fig. 4 is an enlarged face view of the 75 section of the treble strings constituting the higher or last two octaves with my improved third partial harmonic bridge therefor, disposed in about the position it will occupy when employed in conjunction with 80 the strings of said section. In this view many of the strings have been omitted for the clearness of illustration; and

Fig. 5 is an enlarged sectional view taken 85 on line 5—5 of Fig. 4 looking in the direction indicated by the arrows.

Like numerals of reference refer to corresponding parts throughout the different views of the drawings.

Referring now more particularly to Fig. 1 90 of the drawing, the reference numeral 7 designates as a whole the metal plate or frame of an upright piano, which frame or plate may be of the ordinary or any well known construction and has mounted in the usual manner on one of its faces a sounding board 8 of the well known construction. 95

Mounted along the opposite face of the metal frame or plate 7 from that on which the sounding board 8 is disposed and in the usual manner, are the bass strings indicated by the numeral 9 and a section or group of the treble strings indicated by the numeral 10, the group of strings 9 or bass strings diagonally overlying the group 10 100 of the treble strings at a sufficient distance to permit of the location and operation of a second partial harmonic bridge for said group 10 or section of the treble strings. This bridge consists of an elongated strip 11 of any suitable material but usually of wood and a series of springs 12 each of 110

which is secured at one of its ends to the front face of the strip 12 and at its other end fixedly secured to a rock shaft 13 which is journaled at one of its ends in a block 5 or post 14 mounted on the board 8 near the longest string of the treble group 10 as is clearly shown in Figs. 1 and 2 of the drawings. The other end of the rock shaft 13 is provided with a crank 15 and is journaled 10 near said crank in a post 16 secured to the front face of the sounding board.

Loosely connected to the crank 15 is an operating rod 17 which extends downwardly through a guide 18 on the block or post 16, 15 and from thence to one of the pedals of the instrument, not shown, to which it may be suitably connected. The bridge member or strip 11 is disposed diagonally across the treble strings of the section 10 as is clearly 20 shown in Figs. 1 and 2 of the drawings, and has mounted diagonally on the lower surface thereof a series of spaced leather pads 19 which are so arranged as to contact separately and simultaneously with the three 25 strings or strands comprising each of the notes or strings of the treble section 10 and at right angles thereto.

Located diagonally across the group 9 of the bass strings is a second partial harmonic 30 bridge for the bass strings, which consists of a straight bar or member 20 of wood or other suitable material, which has on its rear surface a leather pad 21 which is preferably of a continuous strip, as shown 35 by dotted lines in Fig. 2 of the drawings. The bar or member is supported on a rock shaft 22 of similar construction to that of the first described bridge by means of 40 springs 12 which are secured at one of their ends to the front surface of the bar 20 and at their other ends to the rock shaft 22 so as to actuate the bar 20 when the rock shaft 22 is turned. This shaft is journaled at one of its ends in the post 14 and near its 45 other end on a part 23 of the post 16. The shaft 22 is provided at its last named end with a crank 24 which is loosely connected to an arm 25 extended from the operating rod 17 so that in the movement of said rod 50 the first harmonic bridge for the said group of treble strings and the first harmonic bridge for the bass strings will be simultaneously operated.

Located across the group of bass strings 55 between the last described first harmonic bridge and the lower ends of said strings, is a second harmonic bridge for the bass strings, which is designated as a whole by the reference numeral 28 and is of the same 60 construction as the harmonic bridge above described for the base strings. The first harmonic bridge for the group 10 of treble strings is indicated as a whole by the reference numeral 26 and the first harmonic 65 bridge for the bass strings is indicated as

a whole by the numeral 27. The rock shaft of the bridge 28 is journaled in posts 30 and 31 located on the sounding board at each side of the group of bass strings, and this bridge is operated by means of a rod or 70 connection 32 connected to one of the pedals of the instrument.

The reference numeral 29 designates as a whole the second harmonic bridge for the group 10 of treble strings and is of substantially the same construction as that of the bridge 26, except that the bar or member 33 which carries the leather pad on its rear surface may have a different shape from the strip 11 of the bridge 26 as is shown in 80 Fig. 1 of the drawings, in which view it will be observed that the bridge 29 is located in its general direction diagonally across the group 10 of the treble strings. The rock shaft 34 of the bridge 29 is journaled at one of its ends on the post 16 and at its other end on a post 35 mounted on the sounding board near the lowest toned string of said treble group. The rock shaft 34 has at its last named end, a crank 36 to which is loosely connected one end of a rod 37 the other end of which is suitably connected to one of the pedals of the instrument in such a way that the shaft 34 can be rocked so as to bring the bridge 29 into or out of contact with the said group of treble strings. 90

It will be observed by reference to Fig. 1 that the strings of the group 10 rest on a supporting rib 38 on the sounding board and that this rib is extended under a group 100 10^a of the treble strings, which last named group produce the higher or last two octaves.

In the construction of pianos heretofore and now in general use, the group of strings producing the higher or last two octaves are very short, as is well known, and would, if used, terminate at their lower ends just below the dotted line position of the rib 38 shown in Figs. 1 and 4 of the drawings. An important object of my invention is the elimination of these short strings comprising the group 10^a of treble strings, and substituting therefor strings of much greater length and further in regulating the tuning 110 of said elongated strings and applying thereto for constant contact therewith, what I will term a constantly contacting second harmonic bridge, which is designated as a 115 whole by the reference numeral 39, see Figs. 1, 4 and 5 of the drawings. 120

The bridge 39 consists of a bar 40 of any suitable material, which is resiliently supported on the sounding board 8 by means of a plurality of bow springs 41 interposed between the said beard and bar and secured to the latter, as is clearly shown in Fig. 5 of the drawings. By this arrangement it is manifest that as the treble strings of the group 10^a are stretched over the bridge 39, 130

the upper surface of which may be provided with padding 42 such as leather, will be constantly pressed against the strings 10^a at suitable points.

5 The partial tone bridges are so named for the reason the natural harmonics, commonly called partial tone or partial, are effectively produced when said bridges are brought in contact with the strings at certain nodal points, e. g., the string vibrating its full length, produces the prime or fundamental or first partial tone; at the exact center of the length of the open strings the second partial tone harmonic will be produced; at 15 one-third of the length of the open strings the third partial; at one-fourth of the length of the open strings the fourth partial, and so on.

In Figs. 1 and 2 of the drawings the 20 bridge 26 is shown in position for producing the first harmonic for the treble strings, that is, the group 10 thereof, while the bridge 27 is shown in position to produce the first harmonic for the bass strings, and 25 the bridge 28 in position at the nodal points for the production of the second harmonic on the bass strings.

In Figs. 1 and 4 of the drawings, it will be seen and readily understood that if the 30 ordinary short treble strings, terminating as before stated at their lower ends just below the supporting rib 38 were employed, the bridge 26 could be extended thereacross as indicated at the dotted line C—C on Figs. 1 35 and 4 of the drawings, for the production of the harmonic octave on said group of short strings. By eliminating the ordinary or normal short strings and substituting therefor the much longer treble strings as shown 40 in Figs. 1 and 4 and so arranging them by using the bridge 39 at the second harmonic nodal point of said elongated group of treble strings, the second harmonic tone will be produced instead of the second harmonic 45 tone of the "open" tones of the shorter or normal strings, which as is well known are metallic, hard and unsatisfactory from a musical standpoint. The elongated strings comprising the group 10^a with my bridge 39 50 in constant contact therewith, produce greatly improved tones, without any interruption to the chromatic scale of the treble series of the normal piano. To illustrate, the last or short string in the ordinary or 55 treble series, is about one and seven-eighths inches long, and said series of strings are lengthened gradually to the thirtieth string at D, see Fig. 1, near the inner end of the bridge 26. This thirtieth string of the ordinary or normal use, is about eight and seven-eighths inches long. As the thirty-first string of the treble series is a continuation 60 of the chromatic scale downward, the strings of the group 10 are gradually lengthened. In my substitution of the much long-

er strings comprising the group 10^a for the ordinary thirty shorter strings, and by regulating the tuning of said elongated strings and applying the bridge 39, as shown, there is produced greatly improved tones, as substitutes for the normal or usual metallic tones, there being obviously no break in the chromatic scale of the treble series of strings from the basses up to the highest tone.

As the first harmonic bridges 26 and 27 are each connected to the operating rod 17, it is manifest that said bridges will be simultaneously actuated by proper movement of said rod through the instrumentality of the pedal of the instrument so that the said bridges can be placed in contact with their respective sets of strings or held out of contact with the same. When used on a player piano, it is manifest that the record therefor can be so made as to operate the rod 17 and through it the last above named bridges. The other manually operated bridges are separately operable, as is apparent by reference to the drawings and the foregoing description relating thereto.

It will be understood that the second harmonic bridge 28 for the base strings, as well as the second harmonic bridge 29 for the group 10 of the treble strings, is independently operable through the instrumentality of the operating rods 32 and 37 by means of the pedals of the instrument or a properly designed record sheet for a player piano. The second harmonic bridge 29 is virtually 100 a continuation of the second harmonic bridge 28, as will be readily understood by those skilled in the art to which my invention pertains.

While I have shown the first harmonic bridge 26 and the second harmonic bridge 29 as being interposed between the group 9 of bass strings and the group 10 of treble strings, yet, it will be understood that these bridges can be located between the group 10 of the treble strings and the sounding board by simply changing the positions of the rock shafts of said bridges on their respective supporting posts.

It will be obvious to those skilled in the art, that my invention is applicable to the zither type of instruments, it being necessary only to add to the ordinary system of strings for said instrument, a further set of gut harp-strings in the space not utilized in such instruments up to the present time, and so locate them as to be in efficient relation to the said harp-strings of such instruments so that the first harmonic bridge can be applied to the base strings thereof. By this arrangement the ordinary zither can be converted into a harp-toned instrument, thereby affording a compound instrument having the qualities of a combined zither and Italian harp.

From the foregoing and by reference to the drawings it will be readily understood and clearly seen that by my improvements, a musical instrument is afforded in which 5 the harmonic bridges 26, 27, 28, and 29 can be applied to the strings as and when desired, by the performer simply operating the proper pedal or pedals, which, through their connection with the bridges, actuate 10 the same, and that thus desirable musical effects, such as exceptional tonal values, sweetness and flexibility of expression and ease of execution, without any change in technique, will be afforded. Furthermore, 15 that by the employment of the greatly elongated group of treble strings producing the higher or last two octaves and the constantly contacting second harmonic bridge 39, instead of the short strings heretofore used 20 for producing said octaves, flute-like and more desirable tones of the natural harmonics are afforded in lieu of the harsh, wiry and unmusical high tones of said shorter strings.

25 While I have, in the foregoing description and explanation, set forth that the group of elongated strings comprises the treble strings required to produce the last two octaves, yet I desire it to be understood that 30 said group may include more than enough of the treble strings to produce the last two octaves without a departure from the invention.

Having thus fully described my invention, what I claim as new and desire to 35 secure by Letters Patent is:—

1. In a stringed musical instrument, the combination with the strings thereof, of a bridge extended across a plurality of the 40 treble strings of the instrument at points to produce first harmonics, means to actuate said bridge into and out of contact with said plurality of treble strings, a plurality of treble strings other than the first named 45 plurality of said strings for producing the higher or last two octaves being of lengths greatly in excess of the strings heretofore employed for producing the last two octaves, and a bridge extended across said elongated 50 strings in contact therewith at points to produce the second harmonic tones.

2. In a stringed musical instrument, the combination with the strings thereof, of a bridge extended across a plurality of the 55 treble strings of the instrument at points to produce first harmonics, a bridge extended across the bass strings of the instrument for contact therewith at points to produce first harmonics, means to simultaneously actuate 60 said bridges into and out of contact with their respective strings, a plurality of treble strings other than the first named plurality 65 of said strings for producing the higher or last two octaves being of lengths greatly in excess of the strings heretofore employed

for producing the last two octaves, and a bridge extended across said elongated strings in contact therewith at points to produce second harmonic tones.

3. In a stringed musical instrument, the combination with the strings thereof, of a bridge extended across a plurality of the treble strings of the instrument at points to produce first harmonics, another bridge extended across said plurality of treble strings 70 at points to produce second harmonic tones, means to actuate said bridges into and out of contact with said plurality of treble strings, a plurality of treble strings other than the first named plurality of strings for producing the higher or last two octaves being of lengths greatly in excess of the strings heretofore employed for producing the last two octaves, and a bridge extended across said elongated strings in contact 75 therewith at points to produce second harmonic tones.

4. In a stringed musical instrument, the combination with the strings thereof, of a bridge extended across a plurality of the treble strings of the instrument at points to produce first harmonic tones, another bridge extended across said plurality of treble strings at points to produce second harmonic tones, means to actuate said bridges into and out of contact with said plurality of treble strings, a bridge extended across the bass strings of the instrument at points to produce first harmonic tones, means to actuate the last named bridge into and out of contact with said bass strings, a plurality of treble strings other than the first named 90 plurality of said strings for producing the higher or last two octaves being of lengths greatly in excess of the strings heretofore employed for producing the last two octaves, and a bridge extended across said elongated strings in contact therewith at points to produce second harmonic tones.

5. In a stringed musical instrument, the combination with the strings thereof, of a bridge extended across a plurality of the treble strings of the instrument at points to produce first harmonics, another bridge extended across said plurality of treble strings at points to produce second harmonic tones, means to actuate said bridges into and out of contact with said plurality of treble strings, a bridge extended across the bass strings of the instrument at points to produce first harmonic tones, another bridge extended across the bass strings of the instrument and adapted for contact therewith at points to produce second harmonic tones, means to actuate each of the last named bridges into and out of contact with the said bass strings.

6. In a stringed musical instrument, the combination with the strings thereof, of a bridge extended across a plurality of the

treble strings of the instrument at points to produce first harmonic tones, another bridge extended across said plurality of treble strings at points to produce second harmonic tones, means to actuate said bridges into and out of contact with said plurality of treble strings, a bridge extended across the bass strings of the instrument at points to produce first harmonic tones, another bridge extended across the bass strings of the instrument at points to produce second harmonic tones, means to actuate each of the last named bridges into and out of contact with the said bass strings, a plurality of treble strings other than the first named plurality of said strings being of lengths

greatly in excess of the strings heretofore employed for producing the last two octaves, and a bridge extended across said elongated strings in contact therewith at points to produce second harmonic tones. 20

7. A musical instrument including the group or section of the treble strings which produce the higher or last two octaves, said strings being of lengths greatly in excess of the strings heretofore employed for producing the last two octaves, and a spring-actuated bridge extended across said elongated strings in constant contact therewith at points to produce second harmonic tones. 25

FREDERICK O. PEASE.
